ELECTRON DISCHARGE DEVICE

Alfred H. Laidig, Bloomfield, N. J., assignor to
 Westinghouse Electric Corporation, East Pittsburgh, Pa., a corporation of Pennsylvania

Application June 26, 1942, Serial No. 448,555

9 Claims. (Cl. 250—27.5)

1

This invention relates to electron discharge devices generally, and to the generation and utilization of ultra high frequency currents, the invention having reference, more particularly, to novel high frequency radio apparatus including hollow-body resonators.

The type of electron discharge device with which the present invention may be classified, consists essentially of two hollow conducting circuit members or resonators within which fields, comprising standing electromagnetic waves, are adapted to be set up by the passage of a stream of electrons through a restricted part thereof. The said members are so constructed that they have or may be adjusted to have the same resonant frequency. They are also so constructed that electrons pass completely through the field of said restricted part of each member preferably within the period of a minute portion of a half-cycle of the operating resonant frequency of the cavity members. With the electric vector of the electromagnetic field of each member acting along the line of travel of the electrons and upon the latter for a time preferably equal to a minute portion of one-half cycle, successive electrons of the stream will emerge from the restricted part of the initial hollow resonant member, referred to as the buncher, with minute variable velocities and will move through the field-free space separating the restricted parts of the two members, whereby a concentration of electrons will form around electrons of normal velocity, that are preceded by slightly slower electrons and followed by slightly faster electrons. Likewise, diminished numbers of electrons will obtain between bunches consisting of electrons of normal velocity that are preceded by fast electrons and followed by slow electrons. Thus, the electrons of the stream pass a given point in waves of increasing and decreasing density, which waves are caused to pass through the restricted part of the second hollow resonant member, referred to as the catcher, by virtue of the phase relationship between the buncher and the catcher grid voltages which in conjunction with equality, though not necessarily, of the resonant frequency of the two members, electromagnetic waves are excited in the second or catcher member that are stronger at the expense of the direct current energy than those existing in the initial or buncher member. With proper coupling of the electromagnetic waves in the catcher member with those of the buncher member, sustained electromagnetic oscillations will result, such coupling obtaining when proper electric and mag-

2

netic inter-connection is provided between resonators with proper phase relations between their respective fields, that is, when the electron groups pass the mid-point between the restricted portions or poles of the catcher of energy abstracting resonant member when the field in that member is most strongly opposing the proper motions of the electrons therethrough. The majority of the modulated electrons, likewise, pass completely through the restricted portion of the second or catcher resonator, and enter a collector. Since the electron group gathers around the electrons of normal velocity which are preceded by slow electrons and followed by fast electrons, this group of normal velocity electrons should pass the mid-point in the field of the restricted portion of the buncher resonator when that field is changing from zero so that the following electrons will be assisted thereby.

20 Electron streams, in velocity modulated tubes, are of relatively high impedance and match readily the resonators through which they pass. The high electron stream impedance is obtained by means of a high potential, but low stream current. This procedure in the microwave region of a few centimeters wavelength encounters difficulties by seriously limiting the output of the oscillators, etc. to almost useless levels. Since practically there is a definite limit to the stream 25 electron density the only other factor in increasing current is to increase the cross section area of the stream. However, in the prior art, as related to the short microwave region, the resonators are scaled down to such an extent that the 30 orifice area through which the stream passes is much restricted. This reduces the stream current.

The proportional magnitudes of the resonators and streams is at once evident if one considers, 40 in the simplest case, an E_{10} mode in a cubical resonator. This designation refers to an electric vector parallel to the axis (having $n=0$), the frequency of which is independent of the dimensions along this axis (Z) and having only one 45 mode of oscillation with the longest possible wavelength, λ , given by $2\sqrt{2}a$, wherein λ designates wavelengths and a designates the dimension from the center normal to a side of the cube. From this simple relation, we immediately see 50 that, in the microwave region of present concern, the largest resonator dimension is of the order of a fraction of an inch at a few centimeters wavelength.

The effective Q of such a small resonator is ap- 55 preciably influenced by the extent of the orifice

and this in fact varies approximately as a^6/b^3 (assuming plane waves which, of course, are not strictly existant in hollow resonators in general), where b is the area of all the orifices involved. Hence, the ratio of orifice to resonator surface must be kept as small as possible (even though there are modes of oscillation whose fields more or less avoid the orifice) and this is not possible with conventional methods of enveloping the resonators around electron streams, without serious loss in electron stream current and hence output.

An object of the present invention is accordingly to improve upon prior art structures to overcome effectively the deficiencies therein and particularly to increase power output in the microwave range with an increase rather than decrease in the size of mechanism employed.

A further object of the invention is to provide for a central collector toward which electrons converge from a ring-like cathode.

Another object of the invention is to enable the collector to be adequately cooled notwithstanding its central position.

A still further object of the invention is to provide a heater for the cathode adequately supported to have a circumferential position around the cathode and retained from physical contact with the cathode.

Still further objects will appear as the description proceeds both by direct recitation thereof and by implication from the context.

In the accompanying drawings, wherein like numerals of reference indicate similar parts throughout the several views, and wherein preferred physical embodiments of the invention are disclosed by way of example;

Figure 1 is a perspective view of an electron discharge device embodying my invention;

Figure 2 is a vertical section on an axial plane as on line II—II of Figure 3;

Figure 3 is a sectional view on a plane perpendicular to the axis and taken midway of the length of the device, that is to say on a vertical line through the middle of Figure 2;

Figure 4 is a perspective view of one of the grid cages;

Figure 5 is a longitudinal sectional view similar to Figure 2 showing a modification;

Figure 6 is a fragmentary sectional view on line VI—VI of Figure 5; and

Figure 7 is a fragmentary sectional view on line VII—VII of Figure 5.

In the specific embodiment of the invention illustrated in said drawings, the structure provides a generally cylindrical housing 10 the outward assembled form of which presents an outer cylinder 11 of short length with a somewhat smaller cylinder 12 projecting axially therefrom at both ends and yet smaller cylinders 13 projecting from both ends of cylinder 12. The outer cylinder 11 constitutes the cathode and cathode-heater region, the next smaller or intermediate cylinder 12 provides the resonator and field-free area, whereas the small cylinders 13 afford a region for collection of the electrons. These several cylindrical portions of the housing as a group are vacuum sealed so that the entire interior may be an evacuated region with the housing constituting the envelope maintaining the vacuum.

The invention will first be described in a simple form, illustrated in Figures 1 and 2, to acquaint the reader with the subject matter generally, and then added detail will be discussed with reference to the remaining figures of the drawings.

As here shown, the inner cylinder 13 projects axially through the next larger or resonator cylinder 12 which in turn projects axially through the next larger or outer cylinder 11. The construction is such that the outer cylindrical wall 14 of the resonator cylinder in part is the inner cylindrical wall for the annular outer cylinder. Similarly the outer cylindrical wall 15 of the inner cylinder 13 in part is the inner cylindrical wall for the annular resonator cylinder. Within outer cylinder 11, and in the area around the common portion of cylindrical wall 14 is an annular ring of insulation 16, outwardly flanged for supporting purposes and to provide an outer region for a pair of bus-bars 17 engirdling the ring of insulation and held thereby from contact with each other or with the cylinder walls. Sealed input connections 18 are provided for said bus bars from the exterior of said outer cylinder. The circumferentially inner face of the insulation ring 16 is preferably concave and provides adequate depth for reception of heater filament segments 19 shown as short coils of appropriate wire the ends of which project radially through the insulation ring and connect with the two bus-bars 17. The several segments 19 are arranged, with proper insulative spacing, end to end, and accordingly compose a coiled heater making a full convolution, with each segment in electrical parallel to the others. Burning out of one filament segment accordingly does not stop operation of the device as a whole.

A ring-like cathode 20, having side flanges, is carried by said flanges upon said ring of insulation, the emitting portion of the cathode being radially inward from the heater and overlying both the heater and the concave face of the ring of insulation. The diameter of the inner circumference of the cathode is only slightly greater than the outside diameter of the next adjacent outer curved wall 14 of cylinder 12 which is provided with a circumferential opening 21 directly in front of the cathode. Electron emission from the cathode accordingly enters radially through said opening 21 in the common part of wall 14 between outer cylinder 11 and resonator cylinder 12.

Inwardly of the said circular or circumferential opening in said cylindrical wall 14 is an annular field-free space 22 defined by a pair of washer-like plates 23, spaced apart substantially the width of said opening. Said field-free space is annular and extends in a radial direction from proximity of and between the cylindrical walls 14 and 15 of the resonator cylinder. The field-free space 22 is entirely within the confines of the resonator cylinder and the plates 23, accordingly divide the end portions of the cylinder from the middle portion forming the field-free space except for small circular gaps 24, 25 between the peripheries of the plates and cylindrical walls 14 and 15 respectively.

Resonator cylinder 12 has a washer-like or annular end wall 26 at each end thereof hermetically sealed with respect to cylindrical walls 14, 15 and parallel to each other and to the plates 23, within that cylinder. Between each said end wall and plate 23 nearest thereto, perpendicular to both is an intermediate wall 27 which is cylindrical and situated such that the volume of the resonator cylinder, exclusive of the area occupied by the field-free space, is substantially divided in half. Thus are provided two resonator chambers 28, 29 of which one, as 29, is radially within 75 the other, each chamber being annular and the

full length of cylinder 12 with a restricted central portion at gaps 24 and 25 respectively. Intermediate wall 27 is common to both of these resonator chambers and has an aperture 30 through which extends a coupling loop 31 for maintaining resonance in the outer chamber from resonance of the inner one.

Cylindrical wall 15 between resonator cylinder 12 and smaller cylinder 13 is peripherally slotted providing an opening 32 therethrough in close proximity to the space included between field-free space confining plates 23 so that electrons emitted from cathode 20 after passing through field-free space 22 continue into the smaller cylinder 13 through said opening 32. The openings 21 and 32 in the outer and inner cylindrical walls 14 and 15 of the resonator cylinder, as well as the openings to and from the field-free space at the outer and inner peripheries of the aforementioned washer-like plates 23 have appropriate grids 33 thereacross. These grids may each be fabricated as a unit, appearing as a cage shown in detail perspective view by Figure 4. The grids are of generally cylindrical construction, having end hoops 34 and transverse stays 35 edgewise to the electron flow with desired interpositioning of grid wires 36 parallel to the stays to give appropriate grid area by wires and stays.

Within the small cylinder 13 is a generally cylindrical collector electrode 37 the structure of which is the same in all figures of the drawings. It is provided with a plurality of pyramidal cavities 38 the bases of which open outwardly in proximity to the electron-passing opening 32 of the surrounding cylindrical wall 15 of said cylinder 13. Projecting coaxially from opposite ends of this collector are pipes 39 having other pipes 40 within the same so that a cooling medium may be introduced, as through inner pipes 40 to a cooling chamber 41 of the collector and returned outward for discharge by outer pipes 39. Said outer pipes 39 are sealed with respect to the collector and to metal caps 42 at outer parts of the pipes, these caps in turn having glassed seals 43 with the inner cylinder 13. This structure likewise constitutes an appropriate support for the collector.

In operation it will be understood that electrons emitted from the cathode travel in a direction radially inward of the device and pass through the first two grids 33 which are separated by gap 24, and then into the field-free space. The resonance of chamber 28 affects the electrons in their said passage between the grids, modifying the electron stream such that some electrons pass through unaffected as to velocity, other electrons are minutely slowed down, and yet other electrons are minutely speeded up. The magnitude of the modulation is partially dependent upon the field strength between the said grids. The electrons, modified as to velocity, continue their travel through the field-free space 22 with the electrons having normal or unaffected speed overtaking previously dispatched somewhat slower electrons and in turn being overtaken by somewhat speeded-up electrons started at a later moment. The proportional length, or radius, in direction of flow of the electrons, of the field-free space is such that the proper concentration or bunching of electrons takes place between the smaller pair of grids 33 in the gap area 25. The electrons accordingly represent a concentration of energy in the said gap area 25 and are capable of giving up energy to the second resonator chamber 29 when acted on by oscillating electric fields

between the grids in the proper phase in accordance with classical theory. A small amount of this energy is utilized, as indicated above, as feed back through loop 31 to the first resonator chamber 28 in order to modify the flow of other electrons in the gap 24 between the larger first pair of grids 33, so that the cycle of operations above explained may continue. Utilization of energy thus built up in inner or smaller diameter resonator chamber 29 is obtained by means of a suitable output connection such as the coaxial line coupling 44. This coupling is preferably constructed as a copper tube 45 within a sleeve 46 soldered or otherwise vacuum sealed through the resonator wall. The outer end of this sleeve is vacuum sealed to a sleeve 47 which virtually constitutes a continuation of the first sleeve 46 but of a material such as that sold under the trade name of "Kovar" which has a coefficient of expansion substantially equivalent to that of borosilicate glass. A glass cap 48 is sealed to the outer end of this "Kovar" sleeve and completes the vacuum-tight enclosure. Copper tube 45 preferably extends from the resonator wall to the outer end of the "Kovar" sleeve and constitutes a good electrical conductor. A coaxial wire 49 extends through the tube, projecting at opposite ends thereof and providing a loop 50 within the resonator and a loop 51 within the glass cap 48, the ends of the wire in each instance being secured to the next adjacent end of the copper tube. Other output connection, however, may be employed, as found desirable or expedient. It will be seen now that the present structure of the disclosed ultra high frequency device is very simple, due in large part to the compact cylindrical shape, that it can be very accurately built, and when assembled is very rigid. These advantages are important to achieve a resonator structure pretuned in manufacture and without means for tuning in use.

In order that the device may be illustrated as capable of being tuned, I have shown an elaboration of the structure above described, by the illustration of Figures 5 to 7. Equivalent parts in this illustration have been identified by numerals heretofore used but with the addition of a prime mark on the numeral. While some of the parts illustrated in this elaboration are identical with parts shown and described in the more simple disclosure of Figures 1 to 4, and some parts are similar or equivalent thereto, it is believed that repetition of the above description will be found unnecessary. Suffice it to say that as before, a cylindrical cathode 20' is provided (shown in this instance as concave for focussing purposes), the cathode directing electrons through a first pair of grids 33', a field-free space 22', a second pair of grids 33' and thence to the collector 37'. Gaps 24' and 25' exist between the grids, and for tuning purposes it is desired to be able to change the gap distance or spacing of the grids of each pair.

As a means for accomplishing the tuning by change of grid relationship, I have shown both cylindrical walls 14' and 15' flexible and resilient, this being accomplished by corrugating those walls in a direction parallel to the cylinder axis. I likewise prefer to taper these cylindrical walls, that tapering being exaggerated in the drawings in order to emphasize its presence. The outer edges of these cylindrical walls are vacuum sealed, as before, to the end wall of the resonator cylinder 12'. Tuning is obtained by compressing the flexible walls in a direction toward the defining

plates 23' of the field-free space 22' or by permitting the flexible walls to move away from those plates by virtue of the resiliency of the said cylindrical walls.

Appropriate means for compressing or releasing the flexible walls is provided, and for obtaining delicacy of tuning, the means here illustrated enables each flexible wall to be flexed irrespective of flexing of any other cylindrical wall portion. As shown, a protruding cylindrical neck 53, externally threaded as at 52, is provided fixed with respect to the end wall of the resonator cylinder and forming substantially a continuation of cylindrical wall 14'. A smaller collar 54 of similar nature but internally threaded at 55 is provided fixed to the end wall of the resonator cylinder and protruding therefrom substantially as a continuation of cylindrical wall 15'. These collars, as well as associated parts about to be described, appear at both ends of the device, but for simplicity of description the construction at one end only will be given in detail. An adjusting knob 56 internally threaded at 57 to mesh with threads 52 of the collar 53 is provided in the form of a ring concentric with the axis of the device. Similarly, adjusting knob 58 of smaller diameter and having external threads 59 to mesh with threads 55 of collar 54 is also provided concentric with the axis of the device.

A flat ring 60 is carried at its inner periphery in an appropriate peripheral groove in knob 56, said knob being shown as of split nature for enabling the ring 60 to be inserted and retained within the groove. The knob may be rotated with respect to the ring, but since rotation of the knob moves the knob axially by virtue of the threaded mounting thereof, rotation of said knob will accordingly move the ring laterally without necessitating rotation of said ring. Similar to the provision of outer ring 60, an inner ring 61 is provided in conjunction with smaller knob 58. Around the outer cylindrical wall 14' of the resonator in engagement with the peaks of the corrugations thereof is a band 62 parallel to and of substantially the same diameter as the aforementioned adjusting ring 60. At suitable intervals are provided slideable posts 63 perpendicular to and interconnecting said band and ring. Consequently movement of the ring in a direction longitudinally of its axis also moves the band and since the band engages the sloping surface of the resonator cylindrical wall, such movement in an inward direction will compress that wall and move its grid inwardly, whereas movement of the band axially outward will enable the resonator wall to resiliently expand radially and thus adjust the grid to a new position. It is to be understood that the grid in this instance is composed of transverse stays and wires secured directly to the resonator wall so that the expansion and contraction above mentioned may take place. Similarly, the inner resonator wall 15' has a band 64 in engagement therewith, said band being parallel to and of substantially the same diameter as inner adjusting ring 61. This band and ring are connected at intervals by posts 65 thus enabling the inner resilient wall 15' of the resonator to be adjusted and to obtain adjustment of its grid 33'.

All of said posts 63 and 65 are slidably mounted in rigid bearings 66 and are rendered vacuum tight and yet movable by virtue of appropriate flexible diaphragms 67. It is intended that each revolution of the respective knob shall transmit very slight movement to the end of the grid as

sociated with the particular knob. As a result, very fine tuning may be obtained and maintained. Equal manipulation of corresponding knobs at opposite ends of the device keeps the grids parallel, but it will be found that fractional tuning can be obtained by turning only one knob a short ways and thus have the grid very slightly out of parallel with its companion grid. The knobs are preferably suitably marked, as by notches 68 in their peripheries in order that they may be oriented to correct position, or, if preferred, the knobs may be geared together for operating the same in unison and thereby adjust the grids and maintain them constantly in parallelism.

15 I claim:

1. An electron discharge device comprising a cylindrical cathode, cylindrical and coaxial grids within and coaxial to the cathode, means between said grids for providing a field-free space therebetween, and said cathode being spaced radially outward from said means so the electrons from the cathode pass therethrough as a radially converging beam, and a collector coaxial within said grids for receiving said electrons.

25 2. An electron discharge device comprising cylindrical means for producing an electron stream in a path converging substantially perpendicular to the axis of said cylindrical means, a second cylinder constituting a resonator and of less diameter than and coaxial with the first said cylindrical means, said resonator having a radial passage for electrons therethrough radially inward from said first cylindrical means and having radially extending means therein shielding

30 35 a part of said electron path through the resonator and adapted to provide a field free passage for the electrons through said shielded part of the path, said resonator and said radial means adapted to cooperate for bunching electrons from 40 said cylindrical means and extracting energy therefrom, a collector centrally disposed about said axis and in the path of convergence of said electrons, and means extending from and for cooling said collector.

45 3. An electron discharge device comprising cylindrical means for producing an electron stream in a path converging substantially perpendicular to the axis of said cylindrical means, a second cylinder constituting a resonator and of less diameter than and coaxial with the first said cylindrical means, said resonator having a radial passage for electrons therethrough radially inward from said first cylindrical means and having radially extending means therein shielding a 50 part of said electron path through the resonator and adapted to provide a field free passage for the electrons through said shielded part of the path, said resonator and said radial means adapted to cooperate for bunching electrons from said cylindrical means and extracting energy therefrom, a collector centrally disposed about said axis and in the path of convergence of said electrons, said collector having a plurality of outwardly opening cavities for collection of electrons therein, and means extending from and for cooling said collector.

55 4. An electron discharge device comprising a cylindrical cathode, a heater next said cathode, said heater comprising a plurality of heater coil sections end to end and electrically spaced apart, said sections being connected in parallel for simultaneous use, and a central collector within said cathode, whereby electrons from the cathode converge radially therefrom to the collector.

60 5. An electron discharge device comprising a

resonator cylinder of annular cross-section having two fixed coaxial cylindrical walls forming a resonator cylinder of annular cross section, said cylinder being divided medially by a third coaxial cylinder thereby forming outer and inner resonators of which one is larger than and encircles the other, parallel plates in said annular resonator cylinder supported by said third cylinder and leaving gap openings of fixed dimension at the peripheries of said plates between 10 said plates and the said two fixed coaxial cylindrical walls, and cathode means outside of the outer one of the said two fixed concentric cylindrical walls for producing converging streams of electrons through said two cylindrical walls and through the region between said plates, whereby electrons in most separated relation pass the gap of the larger resonator and the electrons in more concentrated relation pass the gap of the smaller resonator and whereby the larger one of said resonators affects the electron velocity to bunch the electrons while in separated relation and the other resonator absorbs more energy from the more concentrated and bunched electrons.

6. An electron discharge device comprising a 25 resonator cylinder of annular cross-section having two coaxial cylindrical walls of flexible and resilient material and of which one is within the other, said cylinder being divided medially by a third coaxial cylinder thereby forming outer and inner resonators each of which has one of 30 said flexible walls as a wall thereof, parallel plates in said annular resonator cylinder supported by said third cylinder and leaving gap openings of variable dimension at the peripheries of said plates between said plates and the said two flexible and resilient walls, cathode means girdling said cylinder for passing a modulated stream of electrons through the said cylinders and through the region between said plates for enabling energy to be derived from said stream by one of said resonators, and adjustable means connected to said walls for flexing said flexible walls and thereby tuning the device.

7. An electron discharge device comprising a resonator cylinder of annular cross-section having two coaxial cylindrical walls of flexible and resilient material and of which one is within the other, said cylinder being divided medially by a third coaxial cylinder thereby forming outer and inner resonators each of which has one of said flexible walls as a wall thereof, parallel plates in said annular resonator cylinder supported by said third cylinder and leaving gap openings of variable dimension at the peripheries of said plates between said plates and the said two flexible and resilient walls, cathode means girdling said cylinder for passing a modulated stream of electrons through the said cylinders and through

the region between said plates for enabling energy to be derived from said stream by one of said resonators, and adjustable means connected to said walls for flexing said flexible walls and thereby turning the device, said means for flexing said flexible walls providing knobs on the exterior of the device and pressure-applying means on the flexible walls operatively connected to said knobs.

8. An electron discharge device comprising a resonator cylinder of annular cross-section having two coaxial cylindrical walls of flexible and resilient material and of which one is within the other, said cylinder being divided medially by a third coaxial cylinder thereby forming outer and inner resonators each of which has one of said flexible walls as a wall thereof, parallel plates in said annular resonator cylinder supported by said third cylinder and leaving gap openings of variable dimension at the peripheries of said plates between said plates and the said two flexible and resilient walls, cathode means girdling said cylinder for passing a modulated stream of electrons through the said cylinders and through the region between said plates for enabling energy to be derived from said stream by one of said resonators, and adjustable means connected to said walls for flexing said flexible walls and thereby tuning the device, said means for flexing said flexible walls providing bands on the flexible walls movable axially and adapted thereby to flex said walls, and said means for flexing said flexible walls also providing exterior rings connected with vacuum seal to said bands.

9. An electron discharge device comprising a resonator cylinder of annular cross-section having two coaxial cylindrical walls of flexible and resilient material and of which one is within the other, said cylinder being divided medially by a third coaxial cylinder thereby forming outer and inner resonators each of which has one of said flexible walls as a wall thereof, parallel plates in said annular resonator cylinder supported by said third cylinder and leaving gap openings of variable dimension at the peripheries of said plates between said plates and the said two flexible and resilient walls, cathode means girdling said cylinder for passing a modulated stream of electrons through the said cylinders and through the region between said plates for enabling energy to be derived from said stream by one of said resonators, and adjustable means connected to said walls for flexing said flexible walls and thereby tuning the device, and threaded knobs having 50 grooves receiving said rings and adapted to move said rings and bands axially by rotation of said knobs.

ALFRED H. LAIDIG.
